LIGHTING FIXTURE

Vearl S. Wince, Newark, Ohio, and Carl X. Meyer, St. Louis, Mo., assignor of one-half to Holophane Company, Inc., New York, N.Y., a corporation of Delaware, and one-half to Day-Brite Lighting, Inc., St. Louis, Mo., a corporation of Missouri

Filed May 9, 1962, Ser. No. 70,055

Term of patent 14 years

(Cl. D48—23)

FIG. 1 is a bottom perspective view of the fixture according to the invention;

FIG. 2 is a bottom plan view of the fixture of FIG. 1;

FIG. 3 is a side elevational view of the fixture of FIG. 1;

FIG. 4 is an end elevational view of the fixture of FIG. 1;

FIG. 5 is a sectional view taken along line 5-5 of FIG. 2; and

FIG. 6 is a transverse sectional view taken along line 6-6 of FIG. 2.

The characteristic features of our design reside in the specific configuration of the lens members in combination with the rectangular shaped housing as shown.

We claim:

The ornamental design for a lighting fixture, as shown and described.
